VAPORIZING POT TYPE BURNER

Herbert M. Reeves, James E. North, and Earl D. Hillebrand, Kankakee, Ill., assignors, by mesne assignments, to Heil-Quaker Corporation, a corporation of Delaware

Application October 1, 1954, Serial No. 459,792

2 Claims. (Cl. 158—91)

The present invention relates in general to liquid fuel burners and, more particularly, to vaporizing pot type burners which find use, for example, in oil burning stoves and furnaces.

The general aim of the invention is to make possible improved and smoothly variable control of the rate of fuel combustion in pot type burners, giving infinitely fine adjustment between the limits of a pilot flame and the maximum high fire flame for which the burner is designed.

Further to that aim, it is an object of the invention to provide an improved pot type burner wherein the exposed surface area of liquid fuel is automatically varied with the rate of fuel feed, the rate of vaporization and combustion thus being smoothly controllable.

Another object of the invention is to provide an improved burner in which time lag in the response of flame height to changes in fuel feed rate is drastically reduced.

Still another object is to provide such a burner in which "runaway" action does not take place, the liquid fuel being partially shielded from the heat of a high flame. Radiated heat from the flame aids in producing the vaporization necessary for the maximum flame, but unduly great vaporization is prevented.

A further object is to provide such a burner which is of simple and economical construction, reliable in operation, and readily dismantled for cleaning purposes.

Other objects and advantages of the invention will become apparent as the following description proceeds, taken in conjunction with the following drawings, in which:

Figure 1 is a vertical section of a pot type burner embodying the features of the invention;

Fig. 2 is a bottom plan view of the pilot housing employed in the burner of Figure 1; and

Fig. 3 is a detailed view in section showing the manner in which the burner pot is supported.

While the invention has been shown and is described in some detail with reference to a particular embodiment thereof, there is no intention that it thus be limited to such detail. On the contrary, it is intended here to cover all modifications, equivalents, and alternative constructions falling within the spirit and scope of the invention as defined by the appended claims.

Referring now to the drawing, a pot type burner 10 here illustrated as an exemplary embodiment of the invention, comprises generally a pot 11 which, in this instance, is substantially in the shape of a cylinder. The pot is formed of very similar upper and lower sheet metal halves 11a, 11b which may be formed to their approximate shapes by the same dies on a metal press, and then finished to their individual configurations. A simple interlocking seam at 12 tightly fixes the two halves together. For supplying primary air to the upper portion of the pot, its side walls are made perforate, that is, formed with a plurality of holes 14 arranged in vertically spaced rows. Primary air is supplied to the bottom portion of the pot through a plurality of holes 15 formed at a down-

2

wardly directed angle in an inturned bead 16. The air entering those holes naturally flows downwardly to strike the surfaces of liquid fuel present in the bottom of the pot, thus readily causing the necessary vaporization.

5 The upper end of the pot 11 is formed with a large central outlet opening 18 and means are provided for mounting the entire pot in a manner such that the opening 18 is aligned with a matching opening 19 in a supporting partition 20. The partition 20 and the top of the pot 11 are shaped and interrelated to define a passage through which secondary air is supplied to and mixed with fuel vapor rising from the interior of the pot in a manner to promote efficient combustion of the fuel. As here shown, the pot 11 is suspended from the apertured partition 20 which, in turn, is fixed, as by welding at its periphery, in a casing 21 defining the main combustion chamber at 22. Self-tapping screws 24, inserted through the partition 20 at points spaced around the opening 19, are engaged with matching holes 25 in the top of the pot. The pot 11 and the partition 20 are curved to define an upwardly and inwardly tapering passage 26 terminating in an annular port 28 just above the opening 18. In this manner, secondary air is drawn up through the annular space between the side walls of the pot 11 and the casing 21, the velocity of such air being increased in the tapering passage 26 so that the air is thrown horizontally into the rising vapors and mixes thoroughly with the latter. Accurate spacing of the pot 11 and partition 20, and thus accurate determination of the area of the port 28 is achieved by the provision of a series of downturned tabs 29 formed in the partition. The screws 24 are merely tightened until the top of the pot is drawn firmly against the tabs 29, the dimension of the port 28 thus being accurately determined each time that the parts are assembled.

In liquid fuel burners of the general type described, the problem of controlling flame height and resultant heat presents real difficulty. Once vaporization and burning of liquid fuel in the bottom of the pot is initiated, the heat supplied by the small flame produces progressively greater vaporization and burning so that without some special provision, a "runaway" action occurs. While various attempts have been made in the past to solve these difficulties and while some prior proposals have resulted in burners which would successfully hold a small pilot flame, none is known which permits perfectly smooth adjustment of the flame level between a pilot flame and the maximum heat for which the burner is designed.

50 In accordance with the invention, the difficulty is solved by so forming the bottom of the pot 11 that the exposed surfaces of liquid fuel supplied thereto varies smoothly and proportionately in area with the amount of the fuel present. In addition, means are provided such that a part of the exposed surface of liquid fuel is subject to direct radiation and heating from a flame in the upper part of the pot only when there is a relatively great amount of fuel present and a high flame is desired.

In the present instance this is accomplished by crowning the bottom 30 of the pot 11 upwardly at its central portion 30a. That is, the pot bottom is formed in a generally upwardly concave shape so that a small amount of fuel present in the pot bottom lies in an annular ring and as more fuel is added, it progresses inwardly toward the pot center, thus exposing a proportionately greater surface area from which vaporization may take place. It will be noted that in order to obtain the maximum advantage of the invention, the pot bottom should smoothly rise from its lowest level at the periphery to its highest level at the central portion so that the exposed surface area of liquid fuel is a direct function of the amount of fuel present.

In order to supply liquid fuel to the bottom of the pot 11 at adjustable rates, a supply tube or pipe 31 is inserted through an appropriate opening 32 in the lower portion of the pot wall and is fixed and sealed, as by welding. Suitable valve means herein shown as a manually controllable cock 34 is provided in the pipe 31 so that the feed rate of fuel input may be smoothly and accurately adjusted.

For the purpose of assuring that a pilot flame may be started and maintained but for preventing "runaway" vaporization of fuel when it covers the entire pot bottom, a pilot chamber 35 is defined in the lower portion of the pot in surrounding relation to the center portion of the bottom 30. In the present instance, this pilot chamber is formed by a sheet metal plate in the shape of a ring 36 having a central opening 38 and supported in spaced relation from the pot bottom by engagement of its periphery on the shoulder 16a formed by the inturned bead 16. Further, an annular or cylindrically shaped pilot housing 39 is disposed vertically in the pot with its lower end resting on the bottom 30 and its upper end extending through the opening 38. The housing 39 may be assembled in place simply by inserting it through the outlet opening 18 and slipping it through the ring 36. The housing is preferably sized to have closely spaced, sliding relation with the inner edge of the ring 36 which forms the opening 38. In order to establish communication between the exterior and interior of the pilot housing 39 and permit liquid fuel to progress from the outer portion of the pot bottom inwardly toward the central portion, the housing 39 is formed with a plurality of circumferentially spaced cut-out slots 40 which render the lower margin of the housing discontinuous. Thus, when only a small amount of fuel is present in the burner and lies in an annular ring, burning vapors may pass through the slots 40 and upwardly through the openings 18 and 19. As more fuel is added to the pot and its exposed surface progresses centrally inward to lie within the housing 39, a greater fuel surface area is created which permits more rapid vaporization and combustion, while the fuel surface lying within the housing 39 is exposed to radiation from the flame so as to have its vaporization rate increased still further. A relatively high and hot flame can thus be obtained; "runaway" vaporization and burning is prevented, however, because the ring 36 and housing 39 shield a large portion of the fuel surface area from the high flame existing in the upper portion of the pot.

It is believed that the operation and advantages of the invention will be apparent from the foregoing description. However, by way of brief summary it may be observed that as fuel is supplied at relatively low feed rate through the pipe 31, it will lie in an annular puddle around the outer edge of the pot bottom owing to the centrally crowned configuration of the latter. The small exposed surface area of the fuel, receiving primary air directed downwardly through the openings 15, produces sufficient vaporization to support a very low or pilot flame. The pilot flame burns within the pilot chamber 35, the flames and vapors licking outwardly through the slots 40 to some extent. An equilibrium condition is obtained by which fuel is consumed at the same rate at which it is introduced so that the small annular surface area of the fuel, and the resultant low pilot flame, are maintained.

As the fuel feed rate is increased by opening the cock 34 to a greater extent, the additional fuel in the bottom of the pot creeps inwardly toward the highest central point 30a. This creates a proportionally larger exposed surface area of the fuel and results in a greater vaporization rate and a higher flame. For any given fuel feed rate, an equilibrium condition will be obtained which results in a stabilized proportional exposed fuel surface area and a corresponding flame level. For example, at an intermediate position of the cock 34, fuel will progress a

slight distance inside the pilot housing 39, creating a larger surface area and greater vaporization rate until fuel consumption exactly matches the input feed rate. A stabilized intermediate flame is thus produced.

- 5 Further, if the cock 34 is opened wide, fuel will be supplied at such a rapid rate that the entire pot bottom will be covered. With the resulting large surface area of the fuel, a high vaporization rate and high flame will be produced. Downward radiation from burning vapors 10 in the upper portion of the pot will serve to further increase vaporization from that portion of the fuel surface which lies within the housing 39. The maximum heat obtainable, therefore, will depend to a large extent upon the size of the housing 39 and the openings 18, 19. 15 Cumulative, or "runaway" vaporization and burning is prevented, nevertheless, by virtue of the fact that the ring 36 and housing 39 shield the outermost surface portion of the fuel from heat radiation of flame in the upper portion of the pot.
- 20 It will be readily apparent that the striking advantages obtained in the present instance result from extremely simple and economical structural formations in the burner components. In the illustrative case of a pot constructed of sheet metal stock, it is but a relatively simple matter to smoothly crown the pot bottom 30 on a press or similar shaping device. Additionally, the present construction permits the pilot housing 39 to be slightly less in diameter than the openings 18, 19 so that for cleaning purposes the housing may simply be lifted out of the pot. Since the pilot ring 36 is adequately supported by resting on the shoulder 16a formed by the inturned bead 16, there is no necessity to spot weld or otherwise rigidly fix the ring within the pot.

We claim as our invention:

- 35 1. In a vaporizing pot type burner, the combination comprising a burner pot having perforate side walls and an imperforate, centrally crowned bottom, said pot having a circular outlet opening at its upper end, an inturned bead formed in the side walls of said pot and having a plurality of primary air openings inclined downwardly toward the pot bottom, a plate having a circular central opening therein, disposed in said pot with its periphery supported by the shoulder formed by said inturned bead, an annular pilot housing extending through and disposed 40 in closely spaced relation to the inner edge of said ring, said housing defining with the lower side walls and the bottom of said pot a pilot chamber, said housing having slots in its lower end communicating between said chamber and the central portion of said pot to thereby permit a pilot flame to exist in the pilot chamber when liquid fuel covers only a small portion of the pot bottom at low fuel feed rates owing to the crowned configuration of the bottom, and to permit a higher flame to exist centrally of said housing when liquid fuel covers a greater portion of the pot bottom at higher fuel feed rates, said housing being of lesser diameter than the pot outlet opening and readily removable therethrough.

- 50 2. In a vaporizing pot type burner, the combination of a generally cylindrical burner pot having a perforate wall, an imperforate bottom, and an outlet opening defined in its upper end; an inturned bead formed in the wall of said pot with a plurality of inclined openings for directing primary air downwardly toward the bottom of the pot, a pilot ring in said pot and supported at its periphery by the shoulder defined by said bead, a cylindrically shaped pilot housing vertically disposed in said pot with its lower end resting on the pot bottom and its upper end extending through said ring, said housing having a series of peripherally spaced slots extending upwardly from its lower end to afford communication between its exterior and interior, and means for supplying liquid fuel to the bottom of said pot at adjustable rates, and means defining the shape of the pot bottom such that liquid fuel supplied at low feed rates lies in an annular

puddle beneath said ring, and at higher feed rates lies in a puddle of greater area extending into said housing, whereby at such higher feed rates said ring shields a portion of the fuel in the pot bottom from high flames in the upper portion of the pot to prevent unduly rapid vaporization of the fuel.
